ADHESIVE COATED ARTICLES

ABSTRACT OF THE DISCLOSURE

The invention is an improvement upon pebble wax coated adhesive articles. Originally, the articles of the prior art were susceptible to disfigurement during handling, shipping, storage, etc., due to scratches upon the wax surface. The improvement consists of reproducing a graphic representation on the outer surface for example, by a halftone printing process and then overcoating with a wax adhesive.

In the manufacturing of adhesively coated bulletin boards in the nature of my prior Patent 2,914,873, issued Dec. 1, 1959, a problem new to the art was encountered. It was found that the pebbled wax coatings peculiar to this patent were highly susceptible to disfigurement from scratches, bruises, and scuff marks received during the manufacturing and shipping of these products, as well as while on display in stores, and when in actual use. This problem seriously increased manufacturing, shipping, and sales costs, through excessive damage, and greatly curtailed the useful life of the products in use.

The object of this invention is to provide a method of manufacturing such pebbled coatings so that minor physical damage to the surface is almost completely invisible.

A comparison between my prior art article and the article produced herein will show the damage is quite apparent and there is an extreme contrast in the texture between the coated surface and the scratched area in the prior art article. A damage to the article produced herein is almost totally invisible, even under intense oblique lighting, and at close range.

This phenomenon occurs in the use of a wide variety of graphic background subjects. It is particularly true of graphic representations of textured surfaces, such as fabrics, wood grains, stone, foliage, and other renderings involving fine graphic detail. The essential factor appears to be that substantial parts of the graphic background ornamentation be composed of closely spaced variations in graphic tones. The most effective form of this being the tonal graduations achieved by what is known as half-tone printing. In this form the graphic material is broken up into multiple dots of varying tonal quality, in the manner of benday screening.

The effect is still further heightened if the pebbled wax overlay does not cover 100% of the surface, but leaves small areas of the background ornamentation exposed, adjacent to some of the fax droplets. Opaque and darkly

2

colored waxes are not suited for the purpose, but all translucent white or light colored waxes will perform in the manner described, and the microcrystalline waxes in white or amber grades are especially well suited.

The background ornamentation may be produced in one or more colors by any of the conventional duplicating techniques, such as etched or engraved plates, used directly, or by offset printing. The supporting surface is also limited only by its suitability as a printing surface, and includes not only paper stock, but most other sheet materials on which the required graphic detail can be reproduced, such as sheet plastics and enameled metals.

As both half-tone printing and the spraying of waxes are well established commercial procedures, they need not be further described here for those skilled in these arts.

I claim:

1. An improved article of manufacture employing an
pebbled wax coating, the improvement consisting of an
20 underlying graphic ornamentation on a substrate, said
ornamentation being composed of closely spaced tonal
variations in the ornamentation, and cooperating with an
overlaid, light, translucent coating of said pebbled wax
so as to camouflage to a high degree, subsequent super-
25 ficial damage to the said pebbled wax coating.

2. An article of claim 1 in which the said graphic orna-
mentation is a representation of a textured surface.

3. An article of claim 1 in which the said graphic orna-
mentation is reproduced by a half-tone printing
30 process.

4. An article of claim 1 in which droplets of the said
wax are spaced apart so that portions of the said orna-
mentation are left exposed adjacent to some of the said
droplets.

35 5. An improved article of manufacture employing an
adhesive pebbled wax coated surface for the purpose of
temporarily adhering articles thereto, said improvement
consisting of the imprinting on a surface of the article
a graphic ornamentation having closely spaced tonal
40 variations, and subsequently overlaying a light, translucent
coating of an adhesive, pebbled wax, the said pebbled
wax and the said graphic ornamentation cooperating to
render surface damage to the said pebbled wax, notably
less visible.
